(57) **CLAIM**

The ornamental design for a telescopic stool, as shown and described.

DESCRIPTION

FIG. 1 is a front, right, and top perspective view of a telescopic stool, showing my design.

FIG. 2 is a rear, left, and bottom perspective view thereof.

FIG. 3 is a left side elevation view thereof.

FIG. 4 is a right side elevation view thereof.

FIG. 5 is a rear elevation view thereof.

FIG. 6 is a front elevation view thereof.

FIG. 7 is a top plan view thereof.

FIG. 8 is a bottom plan view thereof.

FIG. 9 is a front, right, and top perspective view of the telescopic stool of FIG. 1 in an alternate closed configuration; and,

FIG. 10 is a partial enlarged view of an area labeled 10 in FIG. 1 comprising a portion of side walls.

The broken lines shown in the drawings are included for the purpose of illustrating portions of the telescopic stool that form no part of the claimed design.

1 Claim, 10 Drawing Sheets
